UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 14,887, dated March 18, 1884.

Application filed January 28, 1884. Term of patent 3½ years.

To all whom it may concern:

Be it known that I, HENRY HUNT, of Greenville, in the State of New Jersey, have invented a new and original Design for Carpets, 5 of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

15 The group A is shown at the right center and at the left upper and lower corners of the photograph. It consists of a central mass of flowers and leaves over an ornamental-border work. Open-leaf sprays project on all sides.

20 The group B is shown at the upper and lower

parts of the photograph. It consists of a scalloped ornamentation under a large flower and leaf mass, having blossom and leaf sprays projecting on all sides.

The group C is shown at the left center and 25 at the right upper and lower corners of the photograph. It consists of two square ornamented panels, one partly overlying the other, both surrounded by leaf masses with projecting leaf and flower stems.

30 Various smaller groups and figures complete the design as shown in the photograph.

I claim--

The design for a carpet, consisting of the groups A B C and the intervening groups and 35 figures, substantially as shown and described.

HENRY HUNT.
